UNITED STATES PATENT OFFICE.

CHARLES WM. SCHUMANN, OF NEW YORK, N. Y.

SHOW-CASE FOR JEWELS.

SPECIFICATION forming part of Letters Patent No. 294,685, dated March 4, 1884.

Application filed June 22, 1883. (Model.)

To all whom it may concern:

Be it known that I, CHARLES W. SCHUMANN, a citizen of the United States, residing in the city of New York, county of New York, 5 and State of New York, have invented certain new and useful Improvements in Show-Cases for Jewels, fully described and represented in the following specification and the accompanying drawings, forming a part of the same.

10 This invention relates to a case designed and adapted for the storage and exhibition of the unmounted diamonds, pearls, and other classes of jewels and precious stones which are kept in stock by manufacturing jewelers and dealers.

15 It is the object of the invention to provide a case adapted for this purpose in which the jewels can be placed and retained in such position as to be readily inspected without being handled or removed from the case, and in

20 which jewels of different classes or sizes can be so arranged as to facilitate the comparison of the same, and which at the same time is of such a nature that when the jewels are not on exhibition the case and its contents can be 25 readily removed to a safe or other place of security.

To these ends the invention consists in a case constructed and arranged in the manner hereinafter fully explained and particularly 30 pointed out.

In the accompanying drawings, Figure 1 is a perspective view of a box or case embodying the invention. Fig. 2 is a transverse vertical section of the same. Fig. 3 is a like view, 35 showing a modified construction, to be hereinafter explained; and Fig. 4 is a partial transverse vertical section, made upon an enlarged scale, for the purpose of illustrating the operation of the invention.

40 Referring to said drawings, it is to be understood that *a* is a box of rectangular or other desirable form, and composed of wood or other suitable material, and of such a size as to be conveniently handled and stored in a safe or 45 vault. This box is provided with a removable glazed cover, *b*, which is constructed to close over the body, as shown in Figs. 1, 2, and 3, and is provided with a spring-catch or other suitable means for securing it in its 50 closed position. The inside of the box is provided at its bottom with a slab of rubber or other elastic yielding substance, *c*, in which is

made a number of small perforations, *d*, corresponding to the number of jewels which it is designed the box or case shall contain. The 55 perforations *d* may extend entirely through the slab *c*, as shown in the present case, or they may extend only a short distance from its upper surface, and in either case they will preferably be slightly enlarged at their upper 60 ends, so as to more readily receive the projections upon the under sides of the jewels, as indicated in Fig. 4.

Instead of the perforations *d* the slab *c* may be provided with grooves, which will serve 65 the same purpose. The slab *c* is of such thickness that the space left between its upper surface and the glass *e* of the cover will be slightly less than the thickness of the smallest jewel which the case is to contain.

70 In filling the case the cover will be removed and the jewels *i* will be arranged upon the slab *c*, so that the projections upon their under sides will lie in the perforations *d* or the grooves, and the cover will then be closed and 75 fastened. In closing the cover each jewel will be pressed against the slab *c*, which, owing to its elasticity, will yield so as to suit itself to the different jewels, and so as to hold the small as well as the large pressed firmly against 80 the glass *e* and prevent them from moving in the case, as shown in Fig. 4.

By means of a case of this construction a large number of unmounted jewels can be kept 85 permanently in a convenient and desirable condition for exhibition and inspection without the necessity of handling or exposure to dust or dirt, and without incurring any risk of their being lost or misplaced.

The slab *e*, although preferably made of 90 elastic rubber, may, as before stated, be composed of any other suitable elastic material—such as felt, papier-maché, or similar substance; or, instead of being made yielding and elastic, it may be made rigid, as shown in 95 Fig. 3, its perforations being somewhat enlarged and provided with small spiral springs *m*, which will act upon each jewel to hold it pressed against the glass *e*.

When the jewels are of a uniform size, the 100 bottom of the case may be made rigid instead of elastic, as in such case the glass *e* will press upon all the jewels alike, so as to hold them in position.

The slab or block *c*, whether rigid or elastic, may and usually will be provided upon its upper surface with a covering, *n*, of velvet or other ornamental fabric, which will not only add greatly to the appearance of the case, but also serve to show the color and quality of the jewels to better advantage.

I am aware of United States Letters Patent No. 183,614, granted October 24, 1876, and I do not herein claim any of the features shown in said Letters Patent.

What I claim is—

1. In a show-case for jewels, the combination, with the removable glazed cover, of the slab, *c*, of elastic material, substantially as described.
2. In a show-case for jewels, the combination, with the removable glazed cover, of the

slab, *c*, of elastic material, provided with means for holding the jewels in their proper positions, substantially as described.

3. In a show-case for jewels, the combination, with the removable glazed cover, of means by which each jewel is independently pressed against said cover, so that jewels of different sizes may be placed in the same case and all held securely in position, substantially as described.

In testimony whereof I have hereunto set my hand in presence of two subscribing witnesses.

CHAS. WM. SCHUMANN.
